R. B. WOODCOCK

SEWING MACHINE

Filed May 17, 1921

Fig. 3

Fig. 1

UNITED STATES PATENT OFFICE.

REGINALD BOYD WOODCOCK, OF LEICESTER, ENGLAND, ASSIGNOR TO UNITED SHOE MACHINERY CORPORATION, OF PATERSON, NEW JERSEY, A CORPORATION OF NEW JERSEY.

SEWING MACHINE.

Application filed May 17, 1921, Serial No. 470,330, and in Great Britain May 31, 1920.

The present invention relates to machines for securing the unlasted upper to the sole or insole of a boot or shoe by means of a sewn seam.

5 Machines for sewing an unlasted upper to the sole of a shoe comprise a sole support arranged to extend within the shoe and support the sole and upper in position to receive the stitches of the seam. In machines of 10 this character the needle is arranged to pierce the upper and the sole in a plane parallel to the surface of the sole which is supported by the sole support.

It is an object of the present invention to 15 provide a machine of the character above referred to by which work presenting abrupt variations in thickness may be readily sewed without appreciable inconvenience to or care on the part of the operator. More specifically, 20 the primary object of the invention is to provide an improved machine of the character shown in the patent to Richards No. 1,163, 558, dated December 7, 1915, by which the upper of a turned shoe and the sole thereof to 25 which a low flat heel has already been secured may be readily sewed together.

With the above objects in view the present 30 invention contemplates the provision in a machine for sewing an unlasted upper to the sole of a shoe of a sole support for positioning the sole and upper in position to receive the seam together with means by which the operator during the sewing operation can move the sole support quickly so as to compensate for any abrupt variations in the thickness 35 of the work. Preferably, means for limiting the extent of the movement of the sole support are provided which limiting means may be adjustable, so that during the 40 sewing operation no care or attention on the part of the operator is required to produce the exact movements of the sole support to secure the desired results. Also preferably the means for moving the work support during 45 the sewing operation are so arranged that the movement of the sole support away from the stitch forming devices is produced by the operator and the return movement is produced by a spring, so that in passing from a 50 thick portion of the work to a thinner portion no act of the operator is required to cause the desired movement of the work support.

In the specific embodiment of the invention hereinafter described, the sole support is in

the form of a horn such as is illustrated in the 55 patent to Richards above referred to. This sole support or horn is yieldingly and adjustably mounted upon a carrier and the carrier is yieldingly mounted upon a movable support. To enable the horn to be moved away 60 from the stitch forming devices to facilitate the insertion and removal of work, mechanism similar to the mechanism illustrated in the Richards patent is provided for moving the carrier support. To enable the horn to be moved towards and from the stitch forming devices during the sewing operation to 65 compensate for abrupt changes in the thickness of the work, means under the control of the operator are provided for moving the horn 70 carrier with relation to its support.

In addition to the features above referred to the present invention also consists in certain constructions, combinations and arrangements of parts hereinafter described and claimed, the advantages of which will be obvious 75 from the following description.

The several features of the present invention will be clearly understood from an inspection of the accompanying drawings, in 80 which:

Figure 1 is a side elevation, partly in section, of a horn mechanism and work engaging parts of a sewing machine embodying the features of the present invention in their 85 preferred form; Fig. 2 is a front elevation of the lower part of the horn mechanism; and Fig. 3 is a perspective view of the heel end of a shoe of the type hereinbefore referred to in the course of being sewn.

In the machine illustrated in the drawings the needle is indicated at 1, the looper at 3, the thread finger at 5, the horn at 2, the work presser at 4, and the channel guide at 6, these parts being constructed and arranged to operate as in the machine of the Richards patent above referred to. From the lower end of the horn 2 a sleeve 8 extends vertically downward which is rotatably and slidably mounted in a bore in a second sleeve 10. The horn with its sleeve 8 is supported upon a carrier hereinafter described which is movably mounted in the sleeve 10 which constitutes the carrier support hereinbefore referred to in the general description of the machine. The sleeve 10 is arranged to slide vertically in a bearing 12 in the machine frame and has depending from it toward the

rear of the machine lugs 14 between which is pivoted one end of a toggle link 16, the other end of which is pivoted to one end of a second link 18 fulcrumed on the machine frame. The second toggle link has an arm 20 to which is connected a treadle rod 22, the lower end of which is pivoted at the rear end of a treadle 23. Also connected to the treadle near its forward end is a rod 25 which extends upwardly to the driving clutch of the machine. A downward actuation of the forward end of the treadle produces an upward movement of the rod 22 and an actuation of the toggle links to raise the horn and thereby clamp the work at the beginning of sewing. A lost motion connection consisting of a pin and slot connection 27 and 29 between the rod 25 and the treadle permits this upward movement of the horn before the driving clutch is thrown into operation. A spring connection indicated at 31 between the rod 22 and the arm 20 of the toggle link 18 permits a continued movement of the treadle to render the driving clutch active after the toggle links 16 and 18 have been straightened.

Extending vertically through the sleeve 8 upon the horn 2 is a rod 24 threaded at its lower end into a member 26 arranged to be adjusted vertically in the bore in the second sleeve 10, by means to be hereinafter described. The rod 24 just above the threaded portion has on it a shoulder 28 supporting a ball race 30 against the upper face of which bears one end of a spring 32 encircling the rod 24. The upper end of the spring engages a shoulder 34 in the bore in the horn sleeve 8, the horn being thereby yieldingly supported. The rod is provided at its upper end with a hand nut 36 by which it may be rotated to adjust the height of the horn.

The member 26 constitutes the horn carrier above referred to and has formed on it rack teeth 38 meshing with a pinion 40 formed on a horizontal shaft 42 rotatably mounted in bearings formed in the lower end of the sleeve 10. Fastened to the left hand end of the pinion shaft 42, as viewing the machine from the front, is an arm 44 by which the horn may be raised or lowered. The arm is forked at its outer end to receive the upper end of a treadle or knee-lever rod 46 which is slotted at 48 to receive the pin 50 in the arm. Depression of the treadle rotates the shaft 42 to lower the horn. The treadle is returned by a suitable spring and the shaft by a spring 52 fastened at one end to a lug 54 on the arm 44 and at the other end to a projection 56 depending from the lower end of the sleeve 10. The slot 48 in the rod 46 allows the horn to be lowered or raised by the toggle 16, 18 without affecting the treadle rod 46 or the shaft 42. The arm 44 has two faces 58, 60 formed upon it which engage one or other of two pins set in any chosen

two of a series of holes 62 formed in an extension 64 of the second sleeve 10. These faces and pins form stops which determine the positions of the horn heightwise under the influence of the spring 52 or when adjusted by the treadle and by placing the pins in suitable holes in the series these positions are varied.

In sewing together an unlasted boot or shoe upper A and a sole B which has a heel C previously attached to it as by a sewn seam D, which sole may consist of a tread layer of leather with a backing of felt and similarly formed heel or may consist as shown of a single layer of leather suitably channelled and a heel consisting of a single layer of leather, the operator will for instance begin sewing at E at the waist just forward of the heel and the horn at this time will be in raised position. The sewing continues round the forepart until the heel is reached on the opposite side of the shoe at F when the operator, by means of the treadle above described quickly lowers the horn a predetermined amount to allow so nearly for the extra thickness at the heel that no (or no appreciable) adverse influence, such as an evident change of work clamping pressure, arises. No sustained attention is required on the part of the operator who merely has to keep the treadle depressed until, after sewing round the heel, the horn is again raised by the spring 52 when the treadle is released as the sewing passes off the heel portion.

The nature and scope of the present invention having been indicated and a mechanism embodying the several features of the invention in their preferred form having been specifically described, what is claimed is:—

1. A machine for sewing an unlasted upper to the sole of a shoe having, in combination, stitch forming devices including a needle arranged to pierce the upper and sole in a plane parallel to the surface of the sole, a sole support extending within the shoe, means for separating the sole support and stitch forming devices to facilitate the insertion and removal of work, and separate means under the control of the operator for quickly moving the sole support during the sewing operation to compensate for abrupt variations in the thickness of the work.

2. A machine for sewing an unlasted upper to the sole of a shoe having, in combination, stitch forming devices including a needle arranged to pierce the upper and sole in a plane parallel to the surface of the sole, a sole support extending within the shoe, a carrier for the sole support, a support for said carrier in which the carrier is movably mounted, means for moving the carrier support to separate the sole support and stitch forming devices to facilitate the insertion and removal of work, and means under the control of the operator for moving the

carrier with relation to its support during the sewing operation to compensate for abrupt variations in the thickness of the work.

3. A machine for sewing an unlasted upper to the sole of a shoe having, in combination, stitch forming devices including a needle arranged to pierce the upper and sole in a plane parallel to the surface of the sole, a sole support extending within the shoe, a carrier for the sole support, a support for said carrier in which the carrier is yieldingly mounted, means for moving the carrier support to separate the sole support and stitch forming devices to facilitate the insertion and removal of work, means under the control of the operator for moving the carrier with relation to its support during the sewing operation to compensate for abrupt variations in the thickness of the work, and a spring for moving the carrier in the opposite direction.

4. A machine for sewing an unlasted upper to the sole of a shoe having, in combination, stitch forming devices including a needle arranged to pierce the upper and sole in a plane parallel to the surface of the sole, a sole support extending within the shoe, a carrier for the sole support, a support for said carrier in which the carrier is movably

mounted, means for moving the carrier support to separate the sole support and stitch forming devices to facilitate the insertion and removal of work, means under the control of the operator for moving the carrier with relation to its support during the sewing operation to compensate for abrupt variations in the thickness of the work, and adjustable means for limiting the movement of the carrier with relation to its support.

5. A machine for sewing an unlasted upper to the sole of a shoe having, in combination, stitch forming devices including a needle arranged to pierce the upper and sole in a plane parallel to the surface of the sole, a sole support extending within the shoe, a carrier for the sole support, a support for said carrier in which the carrier is movably mounted, a treadle, and suitable connections for moving the carrier support to separate the sole support and stitch forming devices to facilitate the insertion and removal of work, a driving clutch controlling rod connected with the treadle, and means under the control of the operator for moving said carrier with relation to its support during the sewing operation to compensate for abrupt variations in the thickness of the work.

REGINALD BOYD WOODCOCK.
